US00D637921S

(12) United States Design Patent
Houlihan et al.

(10) Patent No.: US D637,921 S
(45) Date of Patent: * May 17, 2011

(54) NON-CONTACT RECHARGEABLE MEDICAL THERMOMETER

(75) Inventors: Keith Houlihan, Miami, FL (US); Craig Sizer, Aventura, FL (US); Abhishek Shrivastava, Miami, FL (US)

(73) Assignee: SanoMedics Development Corporation, Miami, FL (US)

() Term: 14 Years

(21) Appl. No.: 29/367,123

(22) Filed: Aug. 3, 2010

Related U.S. Application Data

(63) Continuation of application No. 29/356,394, filed on Feb. 25, 2010, now Pat. No. Des. 620,819.

(57) CLAIM

The ornamental design for a non-contact rechargeable medical thermometer, as shown and described.

DESCRIPTION

FIG. 1 is a top plan view of a non-contact rechargeable medical thermometer;

FIG. 2 is a front elevational view thereof;

FIG. 3 is a bottom view thereof;

FIG. 4 is a left elevational view thereof;

FIG. 5 is a rear elevational view thereof;

FIG. 6 is a right elevational view thereof; and,

FIG. 7 is an isometric view thereof, showing our design.

The broken line showing of structural features is included for the purpose of illustrating non-claimed subject matter and forms no part of the claimed design.
